(57) **CLAIM**

The ornamental design for a billiard table, as shown and described.

DESCRIPTION

FIG. 1 is a perspective view of a billiard table showing my new design.

FIG. 2 is a front elevational view of the billiard table shown in FIG. 1.

FIG. 3 is a side elevational view of the billiard table shown in FIG. 1.

FIG. 4 is a top plan view of the billiard table shown in FIG. 1; and,

FIG. 5 is a bottom plan view of the billiard table shown in FIG. 1.

The broken line showing of the billiard table pockets is for illustrative purposes only and forms no part of the claimed design.

1 Claim, 5 Drawing Sheets
